OIL HEATER AND VAPORIZER

Filed Nov. 16, 1928

UNITED STATES PATENT OFFICE

CARL P. CHRISTENSEN, OF UTICA, NEW YORK

OIL HEATER AND VAPORIZER

Application filed November 16, 1928. Serial No. 319,866.

This invention relates to an electric heater designed for heating and vaporizing gasoline or other liquid fuels employed for operating internal combustion engines, or the like.

5 The primary object of the invention is to provide an oil heating and vaporizing medium, which may be substituted for the well-known carburetors common to internal combustion engines, said heater being arranged to be mounted within the manifold which distributes the fuel to the several cylinders of the engine, and being so arranged that the gasoline or other liquid fuel passes through the heater where its temperature is 10 raised sufficiently to produce a fine hot vapor which is discharged by the heater into the manifold, from whence it is drawn in its pre-heated and thoroughly atomized state into the cylinders by the action of the pistons. A 15 further object is to provide a glass or silica bulb-like casing, in which is disposed axially a tube of relatively small caliber that conducts the fuel towards the manifold, the arrangement of the casing and tube being such 20 as to provide a space surrounding the tube in which a vacuum is maintained, and wherein the heating and vaporizing of the gasoline is effected electrically by a filament comprising tungsten or other suitable high resistance 25 material, which is coiled around the said tube and forms a part of an electric circuit which may be energized by current derived from a storage battery, or other source; the bore of said fuel tube being free from obstructions, 30 and the flow of the gasoline and the electric current being controlled respectively by a suitable valve and an ordinary switch. And a further object is to generally improve and 35 simplify the instrumentalities for conditioning volatile and other liquid fuels, by reducing the number of parts and cost of construction; to increase the efficiency of internal combustion engines by preheating the fuel to the 40 point of vaporization, as well as to eliminate fuel waste and minimize the hazard of fire due to overflowing or other uncontrollable 45 action of ordinary carburetors and the like.

I attain these objects by the means set forth in the detailed description which fol-

lows, and as illustrated by the accompanying drawing, in which—

Figure 1 is a partial side elevation and partial central vertical section of the manifold of an internal combustion engine common to 55 automobiles, to which my improvement is applied, the latter also being in central vertical section. Fig. 2 is an enlarged partial elevation and partial central vertical section of the heating and vaporizing mechanism. 60 And Fig. 3 is a diagram of the complete electric circuit.

In the drawing, 2 represents conventionally one type of internal combustion engine used for propelling automobiles. 3 represents the 65 usual manifold, by which the cylinders of the engine are supplied with fuel, such as gasoline, and comprises a T-shaped body having a horizontal portion 3' which embraces and communicates with the several cylinders, and a vertical portion or leg 3^a that usually connects directly with a carburetor (not shown). 4 represents the usual steering mechanism, comprising hand-wheel 4', and shaft 4^a, upon 70 which is mounted the usual manual throttle mechanism, including a rod 5, handle 5', and a valve 6, one end 6' of which connects with the rod by a sleeve-coupling 5^a. The bottom end of the leg 3^a is shown formed with a horizontal flange 3^b, which is perforated 75 for attachment to other parts. The leg 3^a of the manifold is shown formed with windows, as 3^c, for the admission of air to dilute and oxidize the gasoline vapor, and this portion of the leg is fitted with an apertured 80 sleeve 3^d, which is rotatable for opening and closing the windows. In the present case, the well-known carburetor is dispensed with, and in its stead is provided an iron or other metal body 7, which is arranged to close the 85 flanged bottom of the manifold, the said body being fitted with a number of threaded studs 7', that engage the perforations of the flange 3^b, and is held rigid by nuts 7^a. The top 7^b of the body 7 is preferably flat and upon this 90 surface is mounted a bracket or support 8, which may consist of hard rubber, or other insulating material, the bracket being formed with an upwardly facing socket 8' and with 95 perforated flanges 8^a, which may be secured 100

to the body by bolts 8^b. The socket 8' extends downwardly through the bracket and its bottom portion is preferably cone-shaped. The socket 8' preferably alines axially and communicates with a relatively small fuel duct 7^c, which extends downwardly and through a reduced portion or neck 7^d, the said duct being supplied with the liquid fuel by a pipe 9, which is secured to the neck by a gland 9'. In practice, the gasoline is preferably strained before it enters the duct 7^c, and for this purpose a disc of chamois 9^a is disposed between the neck 7^d and the gland 9', as shown in Fig. 2. The body 7 is formed with a laterally extending threaded arm 7^e, which is bored out and threaded, as at 7^x, to receive the valve 6, the valve being supported and guided by a gland 6^e. The valve opening 7^x intersects the duct 7^c at an angle, and the valve is formed with a cone tip 6^a, which may be ground into a correspondingly shaped portion of the socket 7^x.

My heater and vaporizer comprises a glass or other bulb 10, whose lower end, as 10', is reduced and is preferably encased in and reinforced by a brass or other metallic ferrule 12, which directly engages the socket 8'. Both the neck 10' and the ferrule 12 are cone-shaped to conform to the lower portion of the socket 8', and the tips of said cones preferably extend below the plane 7^b of the body 7, the ferrule usually being ground to effect a tight seating in a cone-shaped socket 7^t which registers with the duct 7^c. 13 represents a glass or silica tube that passes axially through the bulb 10, alines and communicates with the duct 7^c, and forms an extension as well as the terminus of the gasoline line. The bore of the tube 13 is preferably extremely small, being but a few thousandths of an inch in diameter, so as to suitably restrict the flow of the fuel. The tube 13 where it enters and emerges from the bulb 10 is preferably fused for facilitating the creation of a vacuum in the annular space 10^a that surrounds the tube. When the lamp 10 is mounted in the bracket 8, as shown, the flow of the gasoline is regulated entirely by the valve 6, which is capable of the finest adjustment. The heating element comprises a filament or wire 14, such as tungsten, or the like. This wire enters at one side of the neck 10', thence extends upwardly towards the top of the enlarged portion of the bulb, where it is coiled downwardly around the tube 13 a suitable number of convolutions, as at 14', and then passes out through the opposite side of the neck 10'. The wire 14 also passes through openings 12' of the ferrule 12, and when the lamp is applied to the support 8, the loose ends thereof are first passed through openings 8^a at the opposite sides of the support that registers with the openings 12' of the ferrule. The battery usually carried by an automobile may be utilized for supplying

the current for the heater 14, and the electric circuit may be controlled by any suitable switch, as 15, shown in Fig. 3, which also includes the battery 16.

In practice, the electric current is first turned on the heating coil 14' and is then followed mediately by the opening of valve 6, for starting the upward flow of the gasoline. By strictly adhering to this practice, no raw gasoline or oil is allowed to escape from the vaporizing tube 13 into the manifold to run the risk of being imperfectly atomized before the fuel is drawn into the cylinders. By the present method of preheating the gasoline while it is passing through the tube 13, there can be no waste of the fuel, and besides, when the heating of the liquid fuel is properly regulated the thoroughness of the atomizing within the tube is assured, and this has been found to raise the efficiency of the engine above that of the general run of carburetors in common use. This preheating and complete atomizing of the fuel tends to increase the mileage per gallon of fuel by effecting a more perfect combustion, and also enables the driver of an automobile to more readily and quickly start the engine without loss of time or waste of fuel, especially in cold weather, when the starting is often delayed until the combustion chambers become heated to the proper extent. Furthermore, my preheating and vaporizing mechanism may be installed and operated in connection with Diesel and other stationary engines, and when associated with the modern self-starting mechanisms, greatly simplifies, as well as facilitates the ready starting and efficient operation of such engines.

Having thus described my invention, what I claim is—

A heater for combustion engine fuel including a bulb formed to have a vacuum maintained therein, a fuel carrying tube in the bulb extending through the ends of the bulb, a filament surrounding said fuel-carrying tube and having its ends extending through the bulb, the ends of the tube and of the filament being sealed into engagement with the bulb, the lower end part of the bulb being of reduced diameter and having the extremity thereof of cone-shape, and a metal ferrule surrounding the said reduced end part of the bulb and the cone-shaped end of the latter and formed to receive the filament ends therethrough.

In testimony whereof I affix my signature.
CARL P. CHRISTENSEN.
